UNITED STATES PATENT OFFICE.

ÉMILE GÉRARD, OF LIMOGES, FRANCE, ASSIGNOR TO OLIVER A. GAGER,
OF BROOKLYN, NEW YORK.

DESIGN FOR A PLATE OR DISH.

SPECIFICATION forming part of Design No. 18,707, dated October 30, 1888.

Application filed November 27, 1885. Serial No. 184,131. Term of patent 7 years.

To all whom it may concern:

Be it known that I, ÉMILE GÉRARD, a citizen of the French Republic, residing in Limoges, France, have invented or produced a new and original Design for Dishes, of which the following is a specification.

This design relates to the shape and surface ornamentation of dishes, and is illustrated in the accompanying photographs, in which—

1c Figure 1 is a plan view of the dish, and Fig. 2 is a perspective thereof.

The design pertains both to the shape and to the surface ornamentation of the dish.

The dish is in general of square outline, with 15 its corners cut off, recessed, and rounded. The depressed center of the plate is circular. The four side outlines of the dish are nearly straight, being, in fact, slightly concaved. The corners are formed of two straight lines, 20 *a a*, and a curve or arc, *b*. The lines *a a* join the sides with obtuse angles, and if continued toward each other they would meet with a re-entering obtuse angle. Between them, however, is the arc *b*, which joins them nearly at 25 right angles; or, in other words, the lines *a a* are approximately radii from the center *c* of the arc *b*.

Described around the center *c* in each corner of the dish is a circular pattern, consisting 30 of an inner figure, *A*, which constitutes a complete circle and is bounded on the outer side by the arc *b*, and an outer annular border, *B*, which is complete until it reaches the lines *a a*, by which it is interrupted. The inner figure, *A*, consists of a simulation of a flower in the center, with a circular row of radiating petals around it, around these a circular line, then a circular row of dots, and outside of all another circular line. The border *B* consists 35 of a circular row of figures, *e e*, resembling ovals drawn to a point at their smaller ends, which point inward toward the center *c*. Outside of these is a chain of dots, *d*. The chain of dots *d* is continued around the entire dish, 40 a row, *f*, extending along each outer side, and a circular row, *g*, extending around close to the depressed portion of the dish.

The rim or flange of the plate between the four corners is divided by the chains of dots 45 50 into four separate panels, *C C*. Each of these

is filled with ornamentation, which is alike at opposite ends. In the outer corner, at each end of each panel, is a corrugated space, *h*. Then between two lines is a section of chain, *i*. Then comes a space filled with a zigzag line, *j*, then a space, *k*, containing oval figures, and lastly a center piece, *l*. These several bands or spaces extend diagonally parallel with the respective lines *a a*.

The depressed central portion of the dish 60 has four ornamental figures, *D D*, radiating from the center, and each extending thence toward one of the figures *A B*. Near each figure *A B* is a bar, *m*, then a bar or bars, *n*, and extending thence toward the center is a fan-shaped figure, *p*, consisting of bars or bands merged together at their inner end and expanding toward their outer end, as shown, and curving outwardly just before reaching the bar *n*. Just inside of each figure *p* is a dot or 70 disk, *q*.

In the center of the dish is a rosette, *E*, being a conventionalized double flower with three concentric circles of radial petals. Outside of this, and about midway between it and 75 the junction of the rim of the plate, is an annular border, *G*. This border consists of outer and inner parallel lines, with the space between them filled with inclined or tangential stripes or bars, as shown. The border *G* appears to pass beneath the four figures *D D*.

The surface ornamentation is shown as impressed in low relief. It may, however, be applied in any other way.

I claim as my invention—

1. The design for the dish having the shape as shown and described.
2. The design for the dish having the surface ornamentation as shown and described.
3. The design for the dish having the combined shape and surface ornamentation as shown and described.

In witness whereof I have hereunto signed my name in the presence of two subscribing witnesses.

ÉMILE GÉRARD.
